SPECTACLE FRAME

Raymond F. E. Stegeman, Greece, N. Y., assignor to
Bausch & Lomb Optical Company, Rochester, N. Y.,
a corporation of New York

Application September 15, 1954, Serial No. 32,301

Term of patent 14 years

(Cl. D57—1)

FIG. 1

FIG. 2

FIG. 3

Fig. 1 is a front elevational view of a spectacle frame embodying my design.

Fig. 2 is a top plan view thereof, with the temples fragmentarily shown.

Fig. 3 is a side elevational view thereof.

The essential features of my design are shown in full lines on the drawing.

I claim:

The ornamental design for a spectacle frame, substantially as shown and described.
